SAFETY RAZOR

Oliver H. Clarke, Washington, D. C.

Application October 25, 1943, Serial No. 507,558

8 Claims. (Cl. 30—47)

1

Generically this invention relates to razors, but it more particularly relates to a razor of the safety type of simple construction and wherein the blade, head and guard means are of integral construction.

One of the principal objects of this invention is the provision of a razor constructed from an integral piece of metal bent upon itself to form a base portion and parallelly extending cutting edges disposed in predetermined spaced relation with respect to the base portion.

An important object of this invention is the provision of a double edge blade constituting a shaving head constructed from a single piece of material bent upon itself to provide a horizontal base portion including side members and oppositely extending end portions formed to provide cutting edges arranged in predetermined relation with respect to the side members, said head adapted to be held by its opposite ends for effecting the shaving operation.

A further important object of this invention is the provision of a razor of this character, simple in construction, manufacturable at a negligible cost, wherein an integral piece of material is formed to provide a base portion including spaced guard means, and blade portions having cutting edges arranged in predeterminedly spaced relation with respect to said guard means.

A still further object of this invention is the provision of a razor constructed from an integral piece of metal shaped and formed to provide a base portion including guard means, the free ends of said metal piece constituting blade portions formed with cutting edges predeterminedly arranged with respect to said guard means, such formation constituting a shaving head adapted to be held by its opposite ends for effecting the shaving operation.

A further object of this invention is the provision of a safety razor of this character constructed from an integral piece of suitable material forming a cutting head, and where desired, the provision of a handle of wood, plastic, or other suitable material including means for effecting its ready detachable connection with said head.

With these and other objects in view, which will become apparent as the description proceeds, the invention resides in the construction, combination, and arrangement of parts, herein-after more fully described and claimed, and illustrated in the accompanying drawings, in which

2

like characters of reference indicate like parts throughout the several figures, of which:

Fig. 1 is a sectional view partly in elevation on the line 2—2 of Fig. 2.

Fig. 2 is an enlarged side elevation or front view of a razor produced according to my invention.

Fig. 3 is an enlarged top plan view of Fig. 2.

Fig. 4 is a sectional view partly in elevation 10. with parts in disassociated relation with the spring member compressed.

Fig. 5 is an enlarged sectional view partly in elevation of a modified form of the invention.

Fig. 6 is a similar view to Fig. 5 with parts in 15. disassembled relation.

Fig. 7 is a fragmentary top plan view with the handle removed.

Fig. 8 is an enlarged perspective view of a further simplified modification.

Fig. 9 is a cross section on the line 9—9 of Fig. 8.

Fig. 10 is a bottom plan view of Fig. 8.

The safety razors with which I am familiar, and in addition to the handle, include a blade 25 and other members constituting the razor or cutting head which must be assembled and secured in operative relation before using and disassembled and separately cleaned following their use. This construction not only increases the production cost but adds to the discomfort and difficulty

incident to the shaving operation, especially under the varying conditions of travel, and it was to overcome such disadvantages and inherent cost, and to produce a razor constructed from an

35 integral piece of metal by bending it upon itself to form a base portion having parallel side members and oppositely extending end or blade portions formed with cutting edges arranged in predetermined spaced relation with respect to

40 said side members, said side members constituting guard means and are slotted to permit the lather and cut hairs to escape instead of clogging up the blade edge, said integral construction constituting a cutting head, and, if desired a handle

45 having means for effecting detachable connection with said base portion, that I designed the device forming the subject matter of this invention.

In the illustrated embodiment characterizing 50 this invention there is shown a safety razor A comprising a blade 1 and handle 2.

The blade 1, in the present instance, is formed from a one-piece strip of metal or suitable material and intermediate its length is bent upwardly at the spaced points 3 to form the base

portion 4 and the substantially vertical side members 5, and inwardly at 6 in meeting directions forming the lateral portions 7 and at 8 bent upwardly forming the upstanding portions 9, and at 10 downwardly and outwardly forming the end or blade portions 11, said portions terminating in the parallelly extending sharpened or cutting edges 12 resting on or slightly spaced from the formation 13 formed in the side or guard members 5 by slots 13' in the present instance extending inwardly beyond said side members.

While said strip may be of blade material, it also may be of soft steel or other material hardened and/or tempered along the sharpened edges 12. The ends of the blade portions 11 are inclined as at 11' towards their cutting edges 12 and rounded at the corners 12' to obviate any likelihood of nicking the face or the hands during the shaving operation.

When thus formed said blade constitutes a shaving head or complete razor with guard means and associated cutting edges at opposite sides of the central base portion and when the ends of the head or razor are gripped or held between the thumb and forefinger it may be readily manipulated to effect the shaving operation.

However, I have provided for selective use by those desiring it, a handle 2 which may be constructed from any suitable material such as wood, plastic, or the like. An attaching and locking member 14 is mounted on and suitably secured to the upper end of handle 2 adapted to project into the end of said handle and of a shape to prevent relative twisting of said handle therewith. Said member 14 comprises a pair of normally spaced spring jaws 15 tapering on two of their opposite sides upwardly and outwardly as at 16 and upwardly and inwardly as at 17 to their meeting edges and formed at their thickest points on opposite sides with slots or recesses 18 adapted to automatically engage the opposite walls of the square opening 19 when said jaws are inserted therein to rigidly interlock said handle and razor. It will be seen that the razor and handle may be snapped into locking engagement and disengaged by simply compressing the jaws as shown in Fig. 4 and withdrawing them from the opening 19.

Figs. 5, 6 and 7 illustrate a slightly modified form similar in principal and operation to that shown and described in connection with Figs. 1, 2, 3 and 4, except that a different type of handle connection and somewhat simplified cutting head formation is provided. At the points 8, instead of forming the upstanding portions 9, the strip is bent upon itself forming the short curved portions 20 and the downwardly and outwardly extending end portions 21 terminating in the parallelly extending sharpened and cutting edges 12 positioned in cutting relation with respect to the slotted guard formation 13, formed in the side members 5, similar to the form heretofore described. It will be noted that the blade end portions 21 extend downwardly at a much less angle of inclination than portions 11 and thereby effecting a much thinner shaving head or razor structure than the form shown and described in Figs. 1 to 4, and with a consequent saving in material.

In connection with the latter form the manner of attaching and securing the handle to the razor is also different, in that the handle 2a is formed on its end with a square projection 22 adapted to fit in the square centrally disposed opening 19 formed in the base 4, and is formed with a threaded opening 23 adapted to receive the threaded screw 24, which when tightened secures and locks

the handle to the razor, and the square lug 22 prevents twisting of the razor with respect to the handle.

Figs. 8, 9, and 10 illustrate a further simplified modification. This form constitutes a small compact razor device, requiring no separate handle, adapted to be carried in the pocket, wallet, or the like, similar in principle to the forms above described, and by reason of its additional simplified structural arrangement, effects a still further saving of material and production cost. It, like the other forms, is formed from a one-piece strip of metal and intermediate its length is bent upwardly at the spaced points 3b to form the base portion 4b and the side members 5b, and inwardly and upwardly into substantially meeting engagement at a point in a vertical plane coincident with the longitudinal median line of said base portion, as at 25, forming the converging portions 26 and then folded upon itself as at 27 forming the downwardly extending overlying end blade portions 28 terminating in the parallelly sharpened cutting edges 12b positioned in operative cutting relation with respect to the slotted guard formation 29 of sides 5b. The opposite edges of the blade portions 28 are inclined or tapered inwardly from 27 as at 30, similar to 11', to their cutting edges 12b at the rounded corners 31, similar to 12', to prevent possibility of nicking the face or hands during the shaving operation, as heretofore explained. Said guard formation 29 is similar to the guard formation 13, except that the spaced parallelly extending slots 32 corresponding to slots 13, extend completely across the base portion 4b, sides 5b and a substantial distance beyond said sides upwardly into the inclined converging portions 26. This slotted formation not only tends to prevent clogging but also to facilitate cleaning during and following the shaving operation.

This form owing to its small size and simple, compact, and integral construction, whereby a handle and other attachable parts are eliminated, is especially adaptable for use by military personnel, troops in the field, campers, and travelers in general.

From the above it is apparent that my razor invention without in anyway departing from the principle or scope thereof, is utilizable in different forms, each being constructed from a single piece of material folded upon itself to form a double edge blade shaving head, requiring no assembling of parts, operable with or without a handle as desired, neat and pleasing in appearance, simple in construction, compact in form, yet easily cleaned, manufacturable at a minimum cost, and efficient for the purposes intended.

Although in practice it has been found that the form of the invention illustrated in the accompanying drawings and referred to in the above description as the preferred embodiment is the most efficient and practical, yet realizing that conditions concurrent with the adoption of the invention will necessarily vary, it is well to emphasize that various minor changes in details of construction, proportion and arrangement of parts, may be resorted to within the scope of the appended claims without departing from or sacrificing any of the principles of the invention.

Having thus described the invention, what is desired protected by letters patent is as set forth in the following claims.

I claim:

1. A razor head comprising a piece of sheet metal, said sheet metal being bent to form a hori-

zontally disposed base portion, side members extending upward from the base portion, intermediate portions, and downwardly extending end portions terminating in cutting edges arranged in parallel guarded relation with respect to said side members.

2. A shaving head for a razor, comprising a piece of sheet metal, said sheet metal being bent to form a horizontally disposed base portion, side members extending upward from the base portion, intermediate portions, and downwardly extending end portions terminating in cutting edges arranged in parallel guarded relation with respect to said side members, said side members being slotted.

3. A razor structure, comprising a base portion, side portions extending upward from said base portion, said side portions forming guard means, intermediate upwardly converging portions, and end portions extending downwardly and outwardly from the converging portions terminating in parallel edges, the formation of the edges of said end portions adjacent said cutting edges being tapered to prevent nicking of the hands and face incident to the shaving opera- 25

4. A shaving head for a razor, comprising an integral piece of sheet metal, said sheet metal being bent to form a horizontally disposed base portion, side portions extending upward from the base portion, intermediate portions, and downwardly and outwardly extending end portions, the free edges of said end portions being formed to provide cutting edges, and said sides, base, and intermediate portions being formed with a plural- 30

ity of cut out portions.

5. A razor including a shaving head comprising a piece of sheet material, said material being formed to provide a base portion, upwardly ex- 35

spaced guarded relation with respect to said side portions.

6. A razor including a shaving head comprising a piece of sheet metal, said sheet metal being bent to form a base portion, upwardly extending side portions, inwardly extending intermediate portions in substantial parallelism with said base portion, and upwardly, outwardly and downwardly extending end portions, said side portions forming guard means, and the free edges of said end portions being formed with cutting edges, said edges being arranged in spaced guarded relation with respect to said side portions.

7. A razor structure constituting a shaving head comprising a piece of sheet material, said material being formed to provide a base portion, side members extending upward from the base portion, intermediate inwardly and upwardly extending portions, and outwardly and downwardly extending portions terminating in cutting edges, handle means, and coacting means between said base portion and handle for effecting rigid and detachable connection of the handle with said base portion.

8. A razor structure constituting a shaving head comprising a piece of sheet material, said material being formed to provide a base portion, a side member extending upward from the base portion, an intermediate portion, and a downwardly extending end portion, the free edge of said end portion being formed to provide a cutting edge, said edge being arranged in offset relation with respect to said side member.
